1

In general, the present invention relates to products which are effective against histoplasma capsulatum and coccidioides immitis and, more particularly, the invention relates to water soluble salts of alkyl vanillates which are therapeutically effective against disseminated histoplasmosis and coccidioidomycosis.

In recent years, investigations have shown that the lower alkyl (less than eight carbon atoms) vanillates are effective against histoplasma capsulatum and coccidioides immitis so that certain infections such as disseminated histoplasmosis and coccidioidomycosis may be effectively treated through the use of ethyl vanillate and other lower alkyl vanillates. Indeed, several case histories have dramatically illustrated the general effectiveness of these lower alkyl vanillates against disseminated histoplasmosis.

However, since the lower alkyl vanillates are not water soluble, it has been necessary to dissolve the alkyl vanillates in olive oil, a 40 per cent solution usually being prepared, in order to administer the lower alkyl vanillates to human beings. The olive oil-vanillate solution then has been given orally. Such administration of the vanillates has been necessary because, as pointed out, they are insoluble in water and because solvents, other than oil solvents, of the vanillates such as aqueous methyl cellulose solutions are unsatisfactory.

In order to establish therapeutically effective levels of the vanillates in the human system, it has been necessary to administer large amounts of the lower alkyl vanillate orally in the olive oil solution, but large amounts of the vanillates are toxic to human beings. As a result, there has been a relatively small margin between therapeutically effective doses of the lower alkyl vanillates and the doses which are toxic. The problem, therefore, has been to broaden the margin so as to make possible establishment of higher levels of the alkyl vanillates in the human system while at the same time keeping the amounts of vanillates administered to human beings below toxic levels.

Accordingly, an object of the present invention is to provide new compounds which may be injected into the human system in a manner such that increased amounts of the alkyl vanillates may be introduced into the human system without causing toxicity. As will appear hereinafter, this and other objects of the invention are accomplished by the formation of an alkali metal salt of the lower alkyl (less than eight carbon atoms) vanillates which is water soluble and which will

2

break up in the human system so as to free the alkyl vanillates from the alkali metal so that it may be therapeutically effective against histoplasmosis and coccidioidomycosis. As used herein, the term alkali metal shall consist of sodium, potassium, lithium and ammonium.

In preparing the salts of the invention, an alkali metal lower alkylate (one to four carbon atoms) is usually prepared and the alkylate is then combined with a lower alkyl vanillate, causing a precipitate to be formed. However, the ammonium salt is usually made by introducing ammonia gas into a lower alkyl vanillate solution, thereby producing a precipitate. The precipitate comprises an alkali metal salt of the alkyl vanillate. The mixture is filtered and the precipitate washed with an alcohol and then with ether. After washing, the precipitate is dried and may then be dissolved in distilled water and used against histoplasma capsulatum and coccidioides immitis.

The salts of potassium and lithium are not generally satisfactory for therapeutic use in human beings and therefore, for such therapeutic purposes, the lower alkyl vanillate salts of sodium and ammonium are preferred. The alkali metal salts are soluble in water, as indicated, but the alkali metal separates from the alkyl vanillate when neutralized. Accordingly, when an alkali metal salt of a lower alkyl vanillate is introduced intramuscularly, intravenously, or subcutaneously into human beings, the lower alkyl vanillate separates from the alkali metal and is in a free form to act against histoplasma capsulatum and coccidioides immitis.

It has been found that of the lower alkyl vanillates, iso-butyl vanillate is particularly effective against disseminated histoplasmosis and coccidioidomycosis and that n-propyl vanillate is also very effective. Accordingly, sodium and ammonium salts of these alkyl vanillates are preferably made for use in treating human beings.

As a specific example of the preparation of the salt of the invention, a solution of sodium ethylate was first prepared by placing 42.7 grams of metallic sodium in 2500 cc. of absolute ethanol under reflux conditions. After reflux, the solution was cooled and was then mixed with a cold solution (15° C.) of iso-butyl vanillate which had been dissolved in 1250 cc. of absolute ethanol. Mixing of the two solutions was accomplished by stirring and, after a few minutes of stirring, the mixture became thick with fine white needles of the sodium salt of iso-butyl vanillate. The cooled mixture was filtered and the precipitate

washed with cold anhydrous ethanol and then with large volumes of absolute ether. After washing with the ether, the sodium salt of iso-butyl vanillate was dried. The salt was relatively stable and was very soluble in water, the salt giving a clear solution having a pH between 10 and 11. It was found that the iso-butyl vanillate precipitated from an aqueous solution by the addition of acid to the point where the solution was substantially neutral.

As another example of the preparation of a salt of the invention, a solution comprising 340 grams of iso-butyl vanillate and 1500 cc. of absolute ether was prepared. The solution was prepared in a flask and dry ammonia gas was bubbled into the flask until it became almost solid with a white granular precipitate. The precipitate was filtered and thoroughly washed with cold (15° C.) anhydrous ether and then air dried. In this manner, 89 grams of the ammonium salt of iso-butyl vanillate was prepared, the salt having a slight ammoniacal odor and being soluble in water. The aqueous solution had a pH of about 9.

It was found that the filtrate could again be treated with ammonia gas to give additional amounts of the white granular precipitate of ammonium salt of iso-butyl vanillate. This additional precipitate was filtered and the filtrate again treated with the ammonia gas. Finally, 364 grams of pure ammonium salt of iso-butyl vanillate was obtained.

The ammonium salt is somewhat more satisfactory for use in the treatment of human beings because of its lower pH and, consequently, lower alkalinity.

The ammonium salt of ethyl vanillate was prepared by preparing a solution of 300 grams of ethyl vanillate in 1500 cc. of absolute ether. This solution was then treated with dry ammonia gas and the precipitate recovered as in the previous example.

The ammonium salt of n-propyl vanillate was made by first preparing a cold solution of 300 grams of n-propyl vanillate in 1500 cc. of absolute ether. This solution was also treated with dry ammonia gas until the flask containing the solution became solid with the ammonium salt of n-propyl vanillate. The salt was filtered and washed with absolute ether and air dried. The filtrate was again treated with ammonia gas to recover additional amounts of ammonium salt n-propyl vanillate.

The lithium and potassium salts of the lower alkyl vanillates may be prepared by first preparing a solution of potassium or lithium ethylate, this being accomplished by placing 1.9 moles of either metallic potassium or lithium in 2500 cc. of absolute ethanol and then refluxing the solution. The ethylate solution should be cooled and combined with a cold solution comprising about two moles of a lower alkyl vanillate and 1250 cc. of absolute ethanol. When these solu-

tions are combined, the potassium or lithium salt will precipitate and may be recovered by filtering. A more pure salt may be had by washing the filtered salt with ether and air drying the product.

In the foregoing, I have disclosed certain products which have unusual value in the treatment of disseminated histoplasmosis and coccidioidomycosis. These products may be easily administered to human beings and higher effective therapeutic levels may be achieved in the human body without danger of toxicity.

The various products which are believed to be new are set forth in the following claims.

I claim:

1. An alkali metal salt of a lower alkyl vanillate, said salt being in crystalline form and being soluble in water in amounts sufficient to provide a therapeutically active composition.
2. The sodium salt of a lower alkyl vanillate, said salt being in crystalline form and being soluble in water in amounts sufficient to provide a therapeutically active composition.
3. The ammonium salt of a lower alkyl vanillate, said salt being in crystalline form and being soluble in water in amounts sufficient to provide a therapeutically active composition.
4. An alkali metal salt of ethyl vanillate, said salt being in crystalline form and being soluble in water in amounts sufficient to provide a therapeutically active composition.
5. An alkali metal salt of iso-butyl vanillate, said salt being in crystalline form and being soluble in water in amounts sufficient to provide a therapeutically active composition.
6. An alkali metal salt of n-propyl vanillate, said salt being in crystalline form and being soluble in water in amounts sufficient to provide a therapeutically active composition.
7. A therapeutic compound comprising the sodium salt of iso-butyl vanillate, said salt being in crystalline form and being soluble in water in amounts sufficient to provide a therapeutically active composition.
8. A therapeutic compound comprising the ammonium salt of iso-butyl vanillate, said salt being in crystalline form and being soluble in water in amounts sufficient to provide a therapeutically active composition.
9. A therapeutic compound comprising the sodium salt of n-propyl vanillate, said salt being in crystalline form and being soluble in water in amounts sufficient to provide a therapeutically active composition.
10. A therapeutic compound comprising the ammonium salt of n-propyl vanillate, said salt being in crystalline form and being soluble in water in amounts sufficient to provide a therapeutically active composition.
